ELECTRICAL TESTER

Joseph L. Bonanno, South Orange, N.J., assignor to Rapid Tool and Manufacturing Co., Inc.

Filed Jan. 25, 1971, Ser. No. 109,735

Term of patent 14 years

Int. Cl. D10—05

U.S. Cl. D26—1

FIG. 1

FIG. 2

FIG. 3

FIG. 4

FIG. 5

FIG. 1 is a top plan view of an electrical tester showing my new design;
FIG. 2 is a side elevational view thereof;
FIG. 3 is a bottom plan view thereof;
FIG. 4 is a left end elevational view thereof;
FIG. 5 is a right end elevational view thereof.

I claim:

The ornamental design for an electrical tester, substantially as shown.
